UNITED STATES PATENT OFFICE.

JOHN ATLAS TURLEY, OF COG HILL, TENNESSEE.

CAR-COUPING.

SPECIFICATION forming part of Letters Patent No. 336,875, dated February 23, 1886.

Application filed September 19, 1885. Serial No. 177,582. (No model.)

To all whom it may concern:

Be it known that I, JOHN A. TURLEY, of Cog Hill, in the county of McMinn and State of Tennessee, have invented certain new and 5 useful Improvements in Car-Couplings; and I do hereby declare that the following is a full, clear, and exact description of the invention, which will enable others skilled in the art to which it appertains to make and use the same, 10 reference being had to the accompanying drawings, which form a part of this specification, and in which—

Figure 1 is a longitudinal vertical sectional view of two draw-heads of my improved car-coupling, showing them in the act of coupling. 15 Fig. 2 is a front view of one of the draw-heads. Fig. 3 is a side view of a draw-head, and Fig. 4 is a perspective detail view of the slide within the draw-head.

20 Similar letters of reference indicate corresponding parts in all the figures.

My invention has relation to that class of 25 automatic car-couplings in which a common pin and link are used in the coupling, the pin being supported during the act of coupling by a slide which is forced back by the opposite draw-head, releasing the pin and consummating the coupling; and it consists in the improved 30 construction and combination of parts of the same, as hereinafter more fully described and claimed.

In the accompanying drawings, the letters A A indicate the draw-heads, which are constructed and secured to the cars in the usual 35 manner, the draw-heads having the recesses B for the reception of the links, and the vertical perforations C for the reception of the pins D. The draw-heads are preferably formed with enlargements E at the perforations for the 40 reception of the pins, as shown at F, for the purpose of supporting the pins in a vertical position when drawn up prior to coupling. The slides G, which slide in the recesses of the draw-heads, are formed by a plate bent 45 to form an upper horizontal portion, H, a downwardly-inclined portion, I, having a downwardly-turned lip, J, at its end, and an upwardly-bent doubled portion, K, formed by doubling the plate to form the horizontal 50 and the inclined portion, and thereupon bent upward. The horizontal portion and the in-

clined portion of the slide are provided with perforations L, which register, and which register with the vertical perforations in the top and bottom of the draw-head, the slide 55 fitting within the recess in the draw-head and sliding in the same, the outward movement of the slide being limited by the downwardly-projecting lip of the inclined portion, which bears against a lug, M, projecting from the 60 bottom of the recess of the draw-head. The upwardly-bent doubled portion fits in a correspondingly-shaped recess, N, in the face of the draw-head, and a recess or niche, O, is formed in this recess, extending to the upper 65 end of the same and beyond it, so that the point of a coupling-pin may be inserted between the upwardly-bent portion and the face of the draw-head, for the purpose of prying the slide outward, setting the slide for sup- 70 porting the pin ready for coupling.

The draw-head may be provided with a transverse perforation, P, through which a pin may be inserted, serving to keep the link in a horizontal position, bearing against the 75 upper side of the inner end of the same when a loose coupling has to be made with another car. It will now be seen that when coupling has to take place the slide may be drawn out by means of the pin, which is inserted into the recess or niche, prying the upwardly-projecting portion of the slide out of its recess, and the slide will now have its perforations drawn forward of the perforations in the top and bottom of the draw-head, so that the pin 85 inserted through the upper perforation will be prevented from dropping through and will be held upright by the enlargement around the perforation. When now the draw-heads come in contact with each other, the slide will 90 be pushed in and the perforations will register, so that the pin will be allowed to drop down and engage the link, which at this time has entered the draw-head.

Having thus described my invention, I claim 95 and desire to secure by Letters Patent of the United States—

1. The combination, with a pin-supporting slide having an upwardly-projecting lip, of a draw-head having a recess in its face for the 100 reception of the lip, and having a recess or niche extending beyond the upper edge of the

recess for the insertion of a pin for prying the lip out of the recess, as and for the purpose shown and set forth.

2. The combination of a draw-head having the usual recess and the usual perforations for the pin, a slide sliding in the recess and having a horizontal portion and a downwardly-inclined portion, and having an upwardly-projecting lip at its outer end and perforations in the horizontal portion and in the inclined portion, and a common coupling pin and link, as and for the purpose shown and set forth.

3. The combination of a draw-head having the usual recess and perforation, and having a recess in its face formed with a niche or groove extending beyond its upper edge, a slide in the recess, consisting of a horizontal portion and a downwardly-inclined portion having a downwardly-bent lip at its inner end, and of an upwardly-bent double portion resting in the recess, the inclined and the horizontal portion having perforations registering when the slide is in with the perforations in the draw-head, a pin or lug projecting from

the bottom of the recess in the draw-head and 25 limiting the play of the slide bearing against the downwardly-bent lip, and a common coupling link and pin, as and for the purpose shown and set forth.

4. A pin-supporting slide for a common 30 draw head, consisting of a plate comprising the following elements: a horizontal perforated upper portion, a doubled part at one end of and at right angles to said horizontal portion, a downwardly-inclined part having an aperture 35 registering with the perforation in the upper horizontal part, and a downwardly-projecting lip at the outer end of the inclined part of the plate, substantially as and for the purpose shown and set forth.

In testimony that I claim the foregoing as my own I have hereunto affixed my signature in presence of two witnesses.

JOHN ATLAS TURLEY.
